UNITED STATES PATENT OFFICE.

FRANK T. KNIGHT, OF MACON, GEORGIA.

TRAIN-STOPPING APPARATUS.

1,145,320.

Specification of Letters Patent.

Patented July 6, 1915.

Application filed October 3, 1913. Serial No. 793,222.

To all whom it may concern:

Be it known that I, FRANK T. KNIGHT, a citizen of the United States of America, residing at Macon, in the county of Bibb and 5 State of Georgia, have invented new and useful Improvements in Train-Stopping Apparatus, of which the following is a specification.

This invention relates to improvements in 10 train stopping apparatus and has particular application to automatic train stopping apparatus.

In carrying out the present invention, it is my purpose to provide an automatic train 15 stopping apparatus whereby the propelling power of a car or train as the case may be will be cut off and the brakes applied to bring the train to a standstill in the event of the same entering the danger zone.

20 It is also my purpose to provide an automatic train stopping apparatus whereby the propelling power of the car or train will be automatically cut off in the event of such car running past grade crossings and the 25 like under the action of the propelling mechanism.

Furthermore, I aim to provide an apparatus of the character set forth which will embrace the desired features of simplicity, 30 efficiency and durability, which may be installed and maintained at a minimum expense and one which will be practically weatherproof and reliable in operation.

With the above and other objects in view, 35 the invention consists in the construction, combination and arrangement of parts hereinafter set forth in and falling within the scope of the claims.

In the accompanying drawings; Figure 1 40 is a diagrammatic view of the car carried stopping mechanism. Fig. 2 is a fragmentary side elevation of the locomotive showing the speed reducing mechanism carried thereby. Fig. 3 is an end view of such mechanism, the cover of the casing thereof being removed. Fig. 4 is a horizontal sectional view through the casing, the mechanism being shown in bottom plan. Fig. 5 is a 45 diagrammatic view showing the relative positions of the cylinders of the train stopping mechanism and the speed reducing mecha-

nism and the connections between such cylinders and the throttle lever. Fig. 6 is a vertical sectional view through the controlling cylinder of the speed reducing mechanism. 55

In the practice of my invention, suitable track obstacles are employed and arranged along the trackway and spaced apart appropriate distances. If desired, these track obstacles may be associated with the block signal system of the railway and in such event the obstacles are located adjacent to the entrance of the respective blocks and each connected up with the adjacent semaphore and capable of movement to active and inactive 60 positions so that when the signal blade of the semaphore is at danger the obstacle will be active, while when the signal is at clear the obstacle will be inactive. 65

The car carried stopping mechanism comprises a device for cutting off the propelling power of the car, such device embodying a cylinder 23 within which is mounted for sliding movement a piston 24 equipped with 70 a piston rod 25 extending outwardly of one end or head of the cylinder by way of a stuffing box 26. One end or head of the cylinder 23 is formed with a fluid inlet port 27 while the opposite head thereof is formed with a 75 vent aperture 28 designed to permit the discharge of air from the rear of the piston as the latter slides toward the respective head of the cylinder under the action of the fluid entering the same by way of the port 27. 80

B designates the brake pipe of the air 85 brake system of the car and, as usual, the forward end of such pipe is provided with a cut-off cock 29 by means of which the pipe B may be placed in communication with 90 the brake pipe of another car when the two cars are coupled up. In open communication with the brake pipe B at a point adjacent to the cock 29 is a branch pipe 30 in which is located a cut-off cock 31 and connected to the free end of the branch pipe 95 30 is an air hose 32.

The numeral 33 designates a controlling 100 valve of the rotary type having the stem thereof equipped with a handle 44. The casing of the valve 33 is provided with an inlet port to which the outer end of the hose

32 is connected and with outlet or discharge ports connected with the inlet ports 27 in the particular head of the cylinder 23 by means of conduits or pipes 39 so that when 5 the valve 33 is open communication will be established between the brake pipe and the cylinder 23 whereby the piston will be moved therein under the action of the air.

In the present instance, I have shown my 10 invention as applied to a steam locomotive and the free end of the piston rod 25 is suitably connected with the throttle lever 50 and designed, when moved inwardly under the action of the piston 24, to swing the throttle 15 lever and so close the throttle valve. Thus, communication between the steam space of the boiler and the drive cylinders of the locomotive will be cut off. The side wall of the cylinder 23 at a point adjacent to the 20 head formed with the vent aperture is provided with a discharge port 51 controlled by the piston 24 and designed to effect the discharge of the air within the cylinder to the atmosphere after the piston 24 has completed its movement to close the throttle 25 valve.

In practice, the controlling valve 33 of the car carried stopping mechanism is fastened upon the side of the car in such manner that 30 the handle 44 thereof extends outwardly to a position to engage the active track obstacles. Should a signal be set at danger the adjacent track obstacle will be in active position, and should a train or car attempt to 35 enter the danger zone against the signal the handle 44 will impact against the active obstacle. As the handle 44 contacts with the trip arm the valve 33 will be opened thereby establishing communication between the 40 brake pipe B and the cylinder 23 by way of the branch pipe 30, the cock 31, the latter being open, the hose 32, the valve casing and the pipes 39. In this position of the controlling valve, the air from the brake pipe 45 enters the cylinder 23 and slides the piston 24 therein so that the throttle valve is moved to closed position to cut off communication between the boiler and the engine cylinders. As the piston 24 moves under the action of 50 the air, the train line air pressure is reduced and the brakes gradually applied and when the piston reaches the limit of its movement under the action of the air, the port 5, in the cylinder is uncovered whereby the air 55 from the brake pipe bleeds into the atmosphere. Thus, the brakes are applied to the wheels and the car brought to a standstill.

In some instances, particularly at grade 60 crossings and analogous places, it is required by the rules and regulations of the railroad that the propelling power of the motor car shall be cut off so that the car or train will "coast" or "roll" over the crossing or like point and in order to automatically cut off

the flow of steam from the boiler to the engine cylinders, in the event of the engineer neglecting to close the throttle valve when the car is passing the crossing, I employ what may be termed a speed reducing mechanism whereby the propelling power of the 65 car is automatically cut off and which is under the direct control of such propelling power. In the present instance, this speed reducing mechanism comprises a substantially rectangular casing 52 suitably secured 70 to the bed frame of the locomotive in advance of the forward truck and below the valve 33. The outer side wall of the casing 52 is preferably hinged so that the same 75 may be thrown to open position when access 80 is desired to the interior of the casing and formed in such movable wall is a slot 54. Suitably secured to the bottom wall of the casing 52 adjacent to the slot 54 is a guide 55 which, in the present instance, is dove tailed 85 in cross section and receives a similarly shaped saddle 56 capable of sliding movement along the guide. Fast to the saddle 56 is a valve 57 constructed in any suitable manner and connected by means of a flexible 90 hose 58 with a source of fluid supply as the main air reservoir of the brake system. Leading out of the casing of the valve 57 are flexible pipes 59, 59 leading into one end 95 of a cylinder 60 disposed adjacent to the cylinder 23 and having a piston therein capable of sliding movement. Projecting outwardly of one end of the cylinder 60 and connected to the piston therein is a piston rod 61, while connecting the outer end of the piston rod 100 61 with the throttle valve lever is a chain 62. It will be noted that the cylinder 60 is relatively short as compared with the length of the cylinder 23 so that the piston therein, when actuated, will move the throttle valve 105 lever to a position to half close the throttle valve. Secured to the bottom wall of the casing 52 in parallelism with the guide 55 is a steam cylinder 63 having one end connected by way of a pipe 64 with the steam 110 chest S of the drive cylinders of the locomotive. Slidably mounted within the cylinder 63 is a piston 65 having the piston rod 66 projecting outwardly of the end of the cylinder opposite to that connected with the 115 steam chest.

Upstanding from the lower wall of the casing 52 at a point approximately centrally of the piston between the cylinder 63 and the guide 55 is a support 67 upon which is 120 mounted for swinging movement a cross arm 68 having one end connected through the medium of a pin and slot connection 69 with the outer extremity of the piston rod 66 and the opposite end connected through 125 the medium of a pin and slot connection 70 with a pin uprising from the saddle 56. By means of this construction, it will be seen

that when the throttle valve is open the steam entering the steam chest S from the steam dome of the boiler will slide the piston 65 within the cylinder 63 and so move the piston rod 66 outwardly of the cylinder thereby swinging the cross arm 68 with the effect to move the saddle 56 along the guide 55 and toward the outer wall of the casing 52. The stem of the valve 57 is equipped 10 with a horizontal handle 71 which projects outwardly of the casing 52 through the slot 54, when the valve is actuated by the piston 65 and the cross arm 68.

At the crossing or a like point, I employ 15 a fixed track obstacle of some suitable construction and disposed in the path of movement of the valve handle 71 when the latter is at its limit of outward movement. Thus, should the train or car pass the fixed obstacle 20 with the throttle valve wide open, the valve handle 71 will be actuated to establish communication between the cylinder 60 and the source of fluid supply by way of the pipe 58, the valve casing and the pipes 59, whereby 25 the piston within the cylinder 60 will be actuated to cut down the flow of steam to the engine cylinder. On the other hand, should the engineer cut off the flow of steam to the drive cylinders of the engine, when approaching 30 the fixed obstacle, the flow of steam to the cylinder 63 will be cut off so that the saddle 56 upon the guide 55 may be restored to normal position and in order to restore the same to normal position automatically, I employ, in the present instance, 35 a coiled contractile spring 73 having one end fastened to the rear end of the saddle and the opposite end secured to the opposite wall of the casing, such spring acting to return 40 the saddle and valve to normal position upon the closing of the throttle valve of the engine.

From the foregoing description taken in connection with the accompanying drawings, 45 the construction and mode of operation of my invention will be readily apparent. It will be seen that I have provided an automatic train controlling system whereby the train will be brought to an immediate 50 stop in the event of the same entering the danger zone, while the flow of steam to the drive cylinders of the engine will be cut down in the event of the engineer passing a grade crossing or other like place with the 55 throttle valve open.

While I have herein shown and described one preferred form of my invention by way of illustration, I wish it to be understood that I do not limit or confine myself to the 60 precise details of construction herein described and delineated, as modification and variation may be made within the scope of the claims without departing from the spirit of the invention.

I claim:

1. In railway controlling apparatus, the combination with the drive cylinder of the engine, of a speed controlling device capable of movement to operative and inoperative positions, means controlled by said device 70 for cutting down the flow of motor fluid to the engine cylinder, means controlled by said fluid for sliding said device to operative position in the normal operation of the engine, and means for rendering said device active 75 when in operative position.

2. In railway controlling apparatus, the combination with the drive cylinder of the engine, means for operating the throttle valve to cut down the flow of motor fluid to 80 the engine cylinder, a valve controlling said means and capable of sliding movement to operative and inoperative positions, a cylinder in open communication with the steam chest of the engine drive cylinder, a piston 85 within said last cylinder, a connection between said piston and valve whereby the latter will be moved to operative position in the normal operation of the drive cylinder, and means for opening said valve when in 90 operative position.

3. In railway controlling apparatus, the combination with the drive cylinder of the engine, of a speed controlling device capable 95 of movement to operative and inoperative positions, means controlled by said device for cutting down the flow of motor fluid to the engine cylinder, means controlled by said fluid for sliding said device to operative position in the normal operation of the 100 engine, means for rendering said device active when in operative position, and means for retracting said device when the flow of motor fluid is cut off from the engine drive cylinder.

4. In railway controlling apparatus, the combination with the drive cylinder of the engine, of a speed controlling device capable 105 of movement to active and inactive positions, means controlled by said device for cutting down the flow of motor fluid to the engine cylinder, a motor operable from said fluid for sliding said device to active position in the normal operation of the engine, and means for bringing said device into service 110 when in operative position.

5. In railway controlling apparatus, the combination with the drive cylinder of the engine, of a speed controlling device capable 115 of movement to active and inactive positions, means controlled by said device for cutting down the flow of motor fluid to the engine cylinder, a motor operable from said fluid for sliding said device to active position in the normal operation of the engine, means 120 for bringing said device into service when in operative position, and means for restoring said device to normal position succeeding.

ing the cutting off of the flow of fluid to the engine cylinder.

6. In railway controlling apparatus, the combination with the drive cylinder of the engine, of a speed controlling device capable of movement to operative and inoperative positions, means controlled by said device for cutting down the flow of motor fluid to the engine cylinder, a motor controlled by said fluid for sliding said device to operative position in the normal position of the engine, means for rendering said device active when in operative position, and a spring for retracting said device when the flow of motor fluid is cut off from the engine drive cylinder.

7. In railway controlling apparatus, the combination with the drive cylinder of the engine, source of supply therefor and the valve controlling communication between the source of supply and drive cylinder, of means operable to actuate said valve to cut down the flow of fluid to said cylinder, and means operable from the motive fluid when the controlling valve is open to move said first means to a position where such means may be rendered active.

8. In a railway controlling apparatus, the combination with the drive cylinder of the engine and the source of fluid supply therefor and the controlling element of the engine, of a motor operable to actuate said element to cut down the flow of fluid to said cylinder, a source of supply for said motor, a valve controlling communication between said last source and motor, and means operable from the motive fluid of the engine when the controlling element is open to move said valve to a position where such valve may be rendered active.

9. In railway controlling apparatus, the combination with the drive cylinder of the engine and the source of fluid supply therefor and the controlling element of the engine, of a motor operable to actuate said element to cut down the flow of fluid to said cylinder, a source of supply for said motor, a valve controlling communication between said last source and motor, and a motor operable from the motive fluid of said engine when said controlling element is open to move said valve to a position where such valve may be rendered active.

10. In railway controlling apparatus, the combination with the drive cylinder of the engine and the source of fluid supply therefor and the controlling element of the engine, of a motor operable to actuate said element to cut down the flow of fluid to said cylinder, a source of supply for said motor, a valve controlling communication between said last source and motor, a motor operable from the motive fluid of said engine when the controlling element is open to move said

valve to a position where such valves may be rendered active, and means for restoring said valve to normal position when communication between the drive cylinder of the engine and the source of fluid supply is cut off.

11. In railway controlling apparatus, the combination with the drive cylinder of the engine and the source of fluid supply therefor and the controlling element of the engine, of a motor operable to actuate said element to cut down the flow of fluid to said cylinder, a source of supply for said motor, a valve controlling communication between said last source and motor, a motor operable from the motive fluid of said engine in the operation of the latter to render said valve active, and a spring for restoring said valve to normal position when communication between the drive cylinder of the engine and the source of fluid supply is cut off.

12. In railway controlling apparatus, the combination with the drive cylinder of the engine, the source of fluid supply therefor and the throttle valve controlling communication between said cylinder and source, a motor operable to actuate said valve to cut down the flow of motive fluid to the cylinder, a source of supply for said motor, a valve controlling communication between said motor and last source and capable of sliding movement to active and inactive positions, means for operating said valve when in active position, and means operable from the motive fluid of the engine in the operation of the latter to slide said valve to active position whereby the throttle valve will be actuated to cut down the flow of fluid to the engine cylinder.

13. In railway controlling apparatus, the combination with the drive cylinder of the engine, the source of fluid supply therefor and the throttle valve controlling communication between said cylinder and source, a motor operable to actuate said valve to cut down the flow of motive fluid to the cylinder, a source of supply for said motor, a valve controlling communication between said motor and last source and capable of sliding movement to active and inactive positions, means for operating said valve when in active position, and a motor operable from the motive fluid of the engine in the operation of the latter to slide said valve to active position whereby the throttle valve will be actuated to cut down the flow of fluid to the engine cylinder.

14. In railway controlling apparatus, the combination with the drive cylinder of the engine, the source of fluid supply therefor and the throttle valve controlling communication between said cylinder and source, a motor operable to actuate said valve to cut down the flow of motive fluid to the cylinder, a source of supply for said motor, a

valve controlling communication between said motor and last source and capable of sliding movement to active and inactive positions, means for operating said valve when

- 5 in active position, a motor operable from the motive fluid of the engine in the operation of the latter to slide said valve to active position whereby the throttle valve will be actuated to cut down the flow of fluid to the
10 engine cylinder, and means for sliding said valve to inactive position succeeding the cutting down of the flow of motive fluid to the engine cylinder.

- 15 In railway controlling apparatus, the combination with the drive cylinder of the engine, the source of fluid supply therefor and the throttle valve controlling communication between said cylinder and source, a motor operable to actuate said valve to cut
20 down the flow of motive fluid to the cylinder, a source of supply for said motor, a valve controlling communication between said motor and last source and capable of sliding movement to active and inactive positions, means for operating said valve when
25 in active position, a motor operable from the motive fluid of the engine in the operation of the latter to slide said valve to active position whereby the throttle valve will be actuated to cut down the flow of fluid to the
30 engine cylinder, and a spring for sliding said valve to inactive position succeeding the cutting down of the flow of motive fluid to the engine cylinder.

- 35 16. In railway controlling apparatus, the combination with the drive cylinder of the engine, the source of fluid supply therefor and the throttle valve controlling communication between said source and cylinder, a motor operable to actuate said throttle valve to cut down the flow of fluid to the drive cylinder, a source of supply for said motor, a valve controlling communication between said last source and motor and capable of
40 sliding movement to active and inactive positions, a motor operable from the motive fluid of the engine in the operation of the latter, a cross arm pivoted between its ends for swinging movement, a pin and slot connection between one end of said arm and
45 said last motor, and a pin and slot connection between the remaining end of said arm and said valve whereby the latter will be slid to active position in the operation of
50 said last motor, and means for opening said valve when the latter is in active position.

- 55 17. In railway controlling apparatus, the combination with the drive cylinder of the engine, the source of supply, the throttle valve controlling communication between said source and cylinder, and the throttle
60 valve operating lever of a controlling device, means controlled by said device for actuating the throttle valve to partially cut down

the flow of fluid to the drive cylinder under 65 certain conditions, and automatic means for actuating the throttle valve to closed position under certain other conditions.

18. In railway controlling apparatus, the combination with the drive cylinder of the 70 engine, the source of supply therefor, the throttle valve controlling communication between said source and cylinder and the throttle valve operating lever of a controlling device capable of movement to active 75 and inactive positions, means operable from the motive fluid of the drive cylinder to move said controlling device to active position, means controlled by said device for actuating the throttle valve to partially cut 80 down the flow of fluid to the drive cylinder under certain conditions, and automatic means for actuating the throttle valve to closed position under certain other conditions. 85

19. In railway controlling apparatus, the combination with the drive cylinder of the engine, the source of supply therefor, the throttle valve controlling communication between said source and cylinder and the 90 throttle valve operating lever of a controlling device capable of movement to active and inactive positions, means for moving said device to active position, means controlled by said device for actuating the 95 throttle valve to partially cut down the flow of fluid to the drive cylinder under certain conditions, and automatic means independent of said last-named means for actuating the throttle valve to closed position under 100 certain other conditions.

20. In railway controlling apparatus, the combination with the propelling mechanism of the motor car, and hand operated means for cutting off the propelling power of the 105 motor car, of a controlling device, means controlled by said device for partially cutting down the propelling power of the motor car under certain conditions, and automatic means independent of said last-named 110 means for cutting off the propelling power of the motor car under certain other conditions.

21. In railway controlling apparatus, the combination with the driving motor of the 115 motor car, the source of supply therefor and the controlling element between the motor and source, of means operable to actuate said element to cut down the flow of motive agent from the source of supply to the motor and capable of movement to a position where such means may be rendered active, and means operable from the motive agent 120 when the controller is in open position to move said first means.

22. In railway controlling apparatus, the combination with the propelling mechanism of the motor car and a hand operated means 125

for cutting off the propelling power of the car, of a controlling device capable of movement to active and inactive positions, means operable by the propelling agent of the motor car to move said controlling device to active position, means controlled by said device for partially cutting down the propelling power of the motor car under certain conditions, and automatic means independ-

ent of said last-named means for cutting off the propelling power of the motor car under certain other conditions.

In testimony whereof I affix my signature in presence of two witnesses.

FRANK T. KNIGHT.
